MOTOR VEHICLE PARKING AND STORAGE SYSTEM

Application filed April 14, 1930. Serial No. 444,280.

The invention relates to parking and storage systems more particularly designed for use in congested districts of cities. In many places of this character the number of cars 5 constantly present is far in excess of the number that can be accommodated by parking on the street, and furthermore, in many districts parking on the street, even for a brief interval, is prohibited. The land values in such 10 locations are much too high to make the erection of a storage garage profitable, and as a consequence the users of cars are obliged to park at some distance from their desired destination and to proceed the rest of the way 15 on foot.

It is the object of our invention to obtain a parking and storage system which will permit car users to drive into the heart of the congested district and will also permit 20 them to proceed under cover to various adjacent points. It is a further object to accomplish this result without excessive costs or the use of valuable building space for unsightly garages. With these objects in view 25 the invention consists in the construction as hereinafter set forth.

In the drawings:

Figure 1 is a plan view of our parking and storage system, partly in horizontal section; 30 Figure 2 is a longitudinal section on line 2-2 of Figure 1;

Figure 3 is a cross section on line 3-3 of Figure 1;

Figure 4 is a view similar to Figure 1 showing a modified construction;

Figure 5 is a similar view showing another modification.

Our improved system is particularly adapted for use upon avenues having spaced 40 roadways for the traffic in opposite directions with a park in between. Such an arrangement is illustrated in Figure 1 in which A and B are the two roadways which are separated by a park space C. Beneath this 45 space C is formed a subterranean parking and storage structure as illustrated in Figures 2 and 3. The space immediately below the ground surface or on the floor D is utilized for the reception of motor cars which 50 find access thereto through ramps E. As

shown, these ramps enter from the roadways at opposite ends of the park, the entrances being covered by the housings E' and the ramps curving inward as they descend to aisles F on opposite sides of a center island platform G. The platform G may be utilized for an office for the cashier or other attendants and may also be provided with a stairway H for ascending to the street level. In alignment with the aisle F and at the opposite end of the park C is an elevator I on which the cars may be lowered to any of the sub-floors D¹, D², D³, D⁴. Preferably the cars are hauled by a suitable tractor instead of being driven under their own power and thus can be transported to any desired location upon the sub-floors. 60

From the floor D a series of tunnels J run in various directions leading to adjacent buildings or points of business so that the occupants of the car may proceed under cover to their destination. Stairways K are arranged at various points for ascending to the street level. 70

When the cars are called for they are preferably raised to the floor D on the elevator I' which is at the opposite end of the park from the elevator I. The cars may then be transported beneath the ramp E through an arch L to the aisle M which is outside of the aisle F and is delivered to the owner adjacent to the point of leaving but in a different aisle. A ramp N is in alignment with the aisle M so that the driver can pass directly out through the covered opening O without crossing any incoming traffic. The space on the floor D between the aisle F and upon opposite sides of the island platform G may be utilized for storage of cars which are only left for short intervals and therefore are 80 more accessible in this location. 85

In the modified construction shown in Figures 4 and 5 there is no central park beneath which the storage may be located. Figure 4 shows the parking structure as arranged beneath the center of a single roadway P having the ramps for entering and leaving on the cross streets as indicated at Q. Figure 5 shows a similar construction but with the reception floor arranged under the sidewalk 90 95 100

and partly under the street or roadway. If desired, the storage may then be in a basement beneath a building adjacent to the roadway. Various other modifications may be made but in all the storage is subterranean rather than in a building which is above the ground level.

What we claim as our invention is:

1. A parking and storage system for motor vehicles comprising a subterranean structure provided with a plurality of storage floors and a reception floor immediately below the ground level, the latter having unobstructed vehicle aisles and a passenger alighting platform adjacent thereto, ramps leading from adjacent roadway to the aisles of said reception floor, and means other than their own power for transporting the motor vehicles from said reception floor to the storage floors, said means being also in line with said unobstructed aisles.

2. A parking and storage system for motor vehicles comprising a subterranean structure located adjacent to a roadway and provided with a plurality of storage floors and a reception floor at the top thereof, first below the ground surface the latter having unobstructed vehicle aisles and a passenger alighting platform adjacent thereto, a series of ramps leading from said adjacent roadway to the aisles of said reception floor, and means other than their own power for transporting the motor vehicles from said reception floor to said storage floor, said means being also in line with said unobstructed aisles.

3. A parking and storage system comprising a subterranean structure located in a congested district and comprising a plurality of superposed storage floors and a reception floor at the top or first below the ground surface, the latter having unobstructed vehicle aisles and a passenger alighting platform ad-

jacent thereto, a plurality of ramps leading from adjacent roadways to the aisles of the reception floor, means other than their own power for transporting motor vehicles from the reception floor to the storage floors said means being also in line with said unobstructed aisles and one or more tunnels leading from said reception floor to adjacent buildings.

4. A parking and storage system comprising a subterranean structure adjacent to a roadway and comprising a plurality of superposed floors with a reception floor at the top or first below the ground surface, having a platform and aisles for incoming and outgoing cars adjacent thereto, ramps leading from an adjacent roadway to the aisles of said reception floor and one or more elevators for transporting the motor vehicles from the reception floor to the storage floors, arranged at the opposite ends of said aisles from said ramps.

5. A parking and storage system for motor vehicles comprising a subterranean structure provided with a plurality of storage floors, and a reception floor immediately below the ground level, the latter having unobstructed vehicle aisles and a passenger alighting platform adjacent thereto, ramps leading from an adjacent roadway to said reception floor, aisles in alignment with said ramps respectively for incoming and outgoing cars, pedestrian passageways from said reception floor and means other than their own power for transporting the motor vehicles from said reception floor to the storage floors.

In testimony whereof we affix our signatures.

NOLAN S. BLACK.
WILFRED V. CASGRAIN.
